UNITED STATES PATENT OFFICE.

DAVID H. SPICER, OF ST. CLOUD, MINNESOTA.

REFRIGERATOR.

SPECIFICATION forming part of Letters Patent No. 308,102, dated November 18, 1884.

Application filed September 2, 1884. (No model.)

To all whom it may concern:

Be it known that I, DAVID H. SPICER, a citizen of the United States, residing at St. Cloud, in the county of Stearns and State of Minnesota, have invented certain new and useful Improvements in Refrigerators, of which the following is a specification, reference being had therein to the accompanying drawings.

10 My invention relates to refrigerators for the proper keeping of provisions, &c.; and the objects of my invention are to produce a simple, inexpensive piece of furniture suitable for use in kitchens, pantries, &c., and the features of 15 the invention will be hereinafter described, and specifically set forth in the claims.

In the accompanying drawings, Figure 1 is a perspective of the refrigerator, showing the ice-chamber closed and the provision-chamber open. Fig. 2 is a transverse vertical section of the same. Fig. 3 is a longitudinal vertical section of the same. Fig. 4 is a perspective view of the top or kneading-board of the refrigerator removed from the frame 25 and standing vertically. Fig. 5 is a perspective view of said top laid in position for use with one of its slides removed.

In the drawings, A represents the outer frame or shell of the refrigerator, the interior 30 of which is divided horizontally by a partition, B, forming the top of the ice-chamber C, and also of the main provision-chamber D, the space under the partition B being divided by the vertical partition c, preferably made of 35 sheet-zinc, having perforations controlled by horizontal slides c². The bottom C' of the ice-chamber is provided with a central opening, c', for the escape of the water from the melting ice, and a grating, C², for the ice to rest 40 upon above said opening c', and under the ice-chamber there is a drawer, E, to receive the water produced by the melting ice. This drawer rests upon the bottom A' of the refrigerator's shell. Both the ice-chamber and the 45 drawer are lined with zinc or sheet metal, e.

Within the provision-chamber D there is placed a shelf, D', preferably formed of rollers d', to support loaves of bread or other provisions. On top of the ice-chamber C and 50 chamber D are placed the meal and flour bins

F and F'. The flour and meal f f', placed in said bins, acts as a non-conductor covering for the chambers C and D, while at the same time the temperature of the flour becomes sufficiently lowered during the summer months to 55 prevent its becoming heated and musty. Above the rear portion of the flour-bins are placed a series of drawers, G, in which spices and other condiments may be placed, thus giving to the refrigerator a high back, through 60 which the ventilating-flues m of the ice and provision chambers are extended and facilitate the removal of vapors and odors from these chambers. The upper end of these flues can be closed, when desired, by means of a 65 sheet-metal slide or of a stopper. The flour-bins are closed by means of a board, H, adapted to be used either simply as a cover or as a kneading-board, whatever may be the side that is the uppermost. For this purpose the 70 board H is pivoted upon pins h, projecting from the ends thereof and passing through slides I, movably secured within the sides of the frame A. When the board H is in position for a kneading-board, its front end may 75 be prevented from tipping down by engaging its rear end under the bottom of the drawers G if the slides I are pushed back as far as possible; but to prevent the forward end of the kneading-board from tipping down while the 80 slides I are pushed back part way only, there is projecting from the side of said kneading-board adjoining the rear end thereof pins k, that are made to engage into grooves i in the under side of the slides I. The same pins k 85 also prevent the inner end of the board H from tipping over the contents of the flour-bins (when said board is turned over and used to simply close them) by engaging with the grooves i², adjoining the end of the slides I. 90 By this construction the refrigerator forms a very useful article of kitchen furniture.

Having thus described my invention, I claim—

1. A refrigerator provided with an ice-chamber, a water-receiving drawer thereunder, a provision-chamber on one side thereof, and flour and meal bins above said chambers, substantially as and for the purpose described.

2. The combination of the drawer E, the 100

provision-chamber D, the bins above said chamber, and the series of drawers G, substantially as and for the purpose described.

3. The combination of the frame A, chamber D, the bins F F', the pivoted cover or board H, provided with pins *k*, and slides I, provided with grooves *i*, substantially as and for the purpose described.

In testimony whereof I affix my signature in presence of two witnesses.

DAVID H. SPICER.
